UNITED STATES PATENT OFFICE.

FRANK HEIMERL, OF ST. NAZIANZ, WISCONSIN.

OIL HEATER FOR CRANK CASES.

Application filed March 4, 1926. Serial No. 92,378.

My invention has for its object to provide a heater to be attached to the crank case of any standard type of internal combustion engine in connection with the exhaust pipe, whereby the exhaust gases may be deflected by valve control from the main exhaust pipe to a pan which will discharge heated gases in juxtaposition to the bottom of the crank case, whereby the oil in cold weather is prevented from congealing.

The attachment can also be utilized in warm weather as a cutout, under which conditions the pan may be removed and the gases will thus be discharged directly through the lead pipe to the pan for cutout purposes, it being understood that a valve manipulated from the dashboard of the vehicle may control the cutout.

With the above and other minor objects in view the invention consists in certain peculiarities of construction and combination of parts as will be hereinafter set forth with reference to the accompanying drawings and subsequently claimed.

In the drawings:—

Figure 1 is a fragmentary side elevation of an engine with the attachment applied;

Figure 2 is an enlarged view of the bottom portion of the device with parts in section;

Figure 3 is an enlarged detail view of the valve portion of the device with parts in section.

Figure 1 represents a fragmentary view of an engine having a standard crank case 1. The standard exhaust pipe which leads to the muffler is indicated at 2 and in this exemplification of my invention the said exhaust pipe is connected to an elbow coupling 3 which is secured to the motor exhaust port by bolts 3' with intermediate flanges of the elbow. The elbow is also provided with a branch nipple 4 having, as best shown in Figure 3, a port 4 that is controlled by any type of valve 5. A valve stem is extended through the elbow and is in crank connection with the dashboard of the vehicle. This valve connection forms no part of my invention and is therefore not illustrated.

The elbow 4 has connected thereto a flexible pipe section 6, to the end of which is fitted a head 7 having a neck 7' which is coupled to the pipe section. The head of the neck 7' merges into a shallow pan 8 which in this particular illustration is centrally apertured for engagement with the

standard oil drain plug 9 whereby the pan is held in position in close proximity to the bottom surface of the crank case 1.

It will be noted that the edge of the pan is spaced from the bottom wall of the crank case a predetermined distance, whereby the spent gases will be discharged in a thin sheet or spray radially from said pan, to thus insure heating the maximum area of the crank case.

From the foregoing description it will be seen that the attachment can readily be fitted to any standard engine by simply supplying the elbow 3 and its associated parts together with a sectional pipe 6 and the heating pan. It is understood that the heating pan may be secured by straps, or other means, in place of being anchored, as shown in Figure 2. Particular attention is directed to the fact that in attaching my heater there are no holes to be bored, or extra parts to be fitted or attached to the engine for assembling. Hence, the skill of a mechanic is eliminated by the purchaser when it is desirable to install the heater, as shown.

It is also within the scope of my invention to vary the shape of the pan heater, the only requirement for said pan being that it is of such shape and proportions that it will directly spray and deflect the exhausted gases upon the surface of the crank case, whereby the heat will serve to prevent the oil from congealing in low temperatures. When the temperature is moderate and it is not necessary to use the crank case heater, I may readily remove the head which comprises the neck portion 7 and the pan 8 from the pipe section 6, whereby said pipe section being open at its bottom will serve as a cutout for the muffler and its associated exhaust pipe 2. That is, the gases by the valve control may be either selectively directed through the muffler or through the drainage pipe 6.

Although the invention has been described in considerable detail, such description is intended as illustrative rather than limiting as the invention may be variously embodied and as the scope of such invention is to be determined as claimed.

I claim:—

1. The combination of an internal combustion engine having an exhaust manifold and having a crank case provided with a drain plug, an attachment of disc-like contour having a central aperture surrounded by an up-

- standing flange and having a marginal flange, said central aperture being adapted to receive the drain plug, whereby the member may be held adjacent the bottom of the 5 crank case with the central flange contacting with the bottom of the crank case and the marginal flange spaced therefrom, said member having an outwardly extending tubular portion opening into such member, and 10 a pipe connection between said exhaust manifold and said tubular portion, whereby exhaust gases are distributed by said member adjacent the bottom of said crank case.
2. The combination of an internal combustion engine having an exhaust manifold and having a crank case provided with an internally threaded drain plug boss, an attach- 15

ment of disc-like contour having an aperture and drain plug passed through said aperture and screwed through the internally 20 threaded drain plug boss to clamp said attachment at the bottom of the crank case, such attachment having a marginal flange and having an outwardly extending pipe connected to said exhaust manifold, and having means adjacent its top for projecting the products of combustion against the bottom of said crank case.

In testimony that I claim the foregoing I have hereunto set my hand at St. Nazianz, in 30 the county of Manitowoc and State of Wisconsin.

FRANK HEIMERL.
